UNITED STATES PATENT OFFICE.

WILLIAM P. JOBSON, OF PHILADELPHIA, AND HARVEY S. SOUDER, OF SOUDERTON, PENNSYLVANIA, ASSIGNORS TO SOUDERTON MANUFACTURING CO., OF SOUDERTON, PENNSYLVANIA, A CORPORATION OF DELAWARE.

AMALGAMATOR.

Application filed April 27, 1921. Serial No. 464,790.

To all whom it may concern:

Be it known that WILLIAM P. JOBSON and HARVEY S. SOUDER, citizens of the United States, residing at Philadelphia and Souder-ton, in the counties of Philadelphia and Montgomery and State of Pennsylvania, have invented certain new and useful Improvements in Amalgamators, of which the following is a specification.

10 This invention relates to metallurgy and has special reference to a device for recovering values from ore, a device being of the type commonly known as an amalgamator.

15 One important object of the invention is to provide an improved and simple form of centrifugal amalgamator.

20 A second important object of the invention is to provide an improved form of continuously operating centrifugal amalgama-tor.

25 A third important object of the invention is to provide, in a device of this class, an improved arrangement of amalgamating chamber.

30 A fourth important object of the invention is to provide an improved arrangement and combination of inlet and outlet pipes in such an amalgamator.

35 With the above and other objects in view, the invention consists in general of certain novel details of construction and combina-tions of parts hereinafter fully described, illustrated in the accompanying drawings, and specifically claimed.

35 The drawing shows a vertical median sec-tion through an amalgamator constructed in accordance with this invention.

40 In carrying out the invention there is provided a lower frame member 10 and an upper frame member 11. These members are connected by spacing bolts 12 and be-tween the two frame members is an interme-diate frame member 13 also supported on these bolts. Mounted in the lower frame member 10 is a foot-step bearing 14 and in the member 13 is a bar 15. Extending through these bearings is a drawoff or ex-haust pipe 16 having a collar 17 resting on the bearing 14 and a second collar 18 rest-ing on the bearing 15. Between the frame members 10 and 13 is a frame member 19 carrying a bearing 20 wherethrough extends a shaft 21 driven by some suitable means, as for instance a belt surrounding a pulley 22.

45 On the shaft 21 is a bevel gear 23 which meshes with a similar gear 24 fixed to the exhaust pipe 16. Screwed on to the upper end of the exhaust is an outer amalgamator bowl 25 and inner amalgamator bowl 26 is likewise screwed on to said pipe above the connection with the bowl 25 so that the inner bowl is held in spaced relation to the outer bowl. The exhaust pipe 16 therein is well up toward the top of the bowl 26 as shown in the drawing.

50 Carried by the upper frame member 11 is a bearing 27 through which extends a supply pipe 28 fixed to the bowl 25 and com-municating with the clear opening 29 of said bowl. In the upper end of the pipe 28 is a connection 30 by means of which this pipe may be connected to a supply pipe. The pipe 30 extends down in a rabbit 31 formed in the pipe 28 and the bearing 27 is ar-ranged to act as a packing gland to hold 55 suitable packing 32 around said pipe 28. By this means the slimes can be fed down-ward through the pipe 28 into the outer bowl 25. In the lower part of the bowl 26 there is provided a plurality of ports 33 and similarly ports 34 provided with stop plugs 35 open from the bowl 25 outwardly. The port 33 afford communication from the space between the inner and outer bolts to the space within the inner bowl. It will 60 be noted that between the openings 33 the inner bowl is provided with an upwardly extending boss 36 having a bevelled upper surface 37 which forms a run-off surface and prevents accumulation in the inner bowl 65 with the consequent gradual hardening and the collection of a mass of amalgam around the draw-off pipe.

70 In operation the bowls are set in rapid rotation by means of the belt pulley 22. 95 The slimes are then fed downward through the pipe 28 and passed into the space be-tween the inner and outer bowls. A quanti-ty of mercury M is placed in the outer bowl and due to the centrifugal action of the ro-tating bowls the mercury rises between the bowls. The slimes are forced down through 100 past mercury and, on reaching the ports 33 pass through these ports and rise up within the inner bowl, the dross being lighter than 105 the mercury. As the slimes pass the mer-cury the gold contained therein amalgamates with the mercury and is retained. The

dross passes upward and overflows the top of the exhaust pipe 16 down which it passes from the amalgamator. From time to time the plugs 35 are removed and the amalgam drawn off, fresh mercury being supplied at such times through the pipe 28.

There has thus been provided a simple and efficient device of the kind described and for the purposes specified.

10 It is obvious that minor changes may be made in the form and construction of the invention without departing from the material principles thereof. It is not therefore desired to confine the invention to the exact 15 form herein shown and described, but it is wished to include all such as properly come within the scope claimed.

Having thus described the invention, what is claimed as new, is:—

20 1. In an amalgamator, a frame, an exhaust pipe journalled vertically in said frame, an outer bowl screwed on the upper end of said pipe, an inner bowl screwed on the upper end of said pipe above the connection of the outer bowl thereto, said bowls being arranged with their sides and tops in spaced relation, said pipe terminating near the top of the inner bowl, said inner bowl having ports opening into the space between 25 the bowl and the outer bowl having normally closed draw off ports, said inner bowl having an upwardly extending boss surrounding said pipe and projecting above the openings, the boss being provided with a 30 frusto-conical upper end, an inlet pipe journalled vertically in the frame and communicating with the top of the outer bowl and having a counter sunk portion in its upper 35 end, a pipe connection having the same internal diameter as the inlet pipe and fitted within the counter sink of said inlet pipe to 40 swivel in relation thereto and means to rotate said bowls.

2. In an amalgamator, a frame, an exhaust pipe journalled vertically in said frame, an outer bowl screwed on the upper end of said pipe, an inner bowl screwed on the upper end of said pipe above the connection of the outer bowl thereto, said bowls being arranged with their sides and tops in spaced relation, said pipe terminating near the top of the inner bowl, said inner bowl having ports opening into the space between the bowls and the outer bowl having normally closed draw off ports, said inner bowl having an upwardly extending boss surrounding said pipe and projecting above the openings, the boss being provided with a frusto-conical upper end, an inlet pipe journalled vertically in the frame and communicating with the top of the outer bowl and having a counter sunk portion in its upper end, a pipe connection having the same internal diameter as the inlet pipe and fitted within the counter sink of said inlet pipe to 45 swivel in relation thereto and means to rotate said bowls comprising a bevel gear fixed to the exhaust pipe, a second bevel gear meshing with the first gear, and a drive shaft journalled in the frame and carrying 50 the second bevel gear.

55 In testimony whereof we affix our signatures.

WILLIAM P. JOBSON.
HARVEY S. SOUDER.
